JAMES T. MURPHY AND EDWARD J. RANEY, OF CHICAGO, ILLINOIS, ASSIGNEES OF
ONE-THIRD TO JAMES L. CAREY, OF CHICAGO, ILLINOIS.

BEATING-ENGINE.

1,310,628.

Specification of Letters Patent. Patented July 22, 1919.

Application filed January 31, 1918. Serial No. 274,192.

To all whom it may concern:

Be it known that we, JAMES T. MURPHY and EDWARD J. RANEY, residing at Chicago, in the county of Cook and State of Illinois, have invented a certain new and useful Improvement in Beating-Engines, of which the following is a full, clear, concise, and exact description, reference being had to the accompanying drawings, forming a part of this specification.

Our invention relates to improvements in beating engines.

The objects of our invention are:

First: To provide means for continuously removing the formed stock from the engine, which will prevent strings, rags, etc., from passing with the formed stock out of the engine. And

Second: To provide means for removing the formed stock from beating engines, including means for separating strings and rags therefrom, of such a character that the strings and rags will not adhere to said means.

Other objects will appear as this description progresses, reference being had to the accompanying drawings, in which:

Figure 1 is a beating engine embodying our invention.

Fig. 2 is an enlarged fragmentary section view through a portion of the beating engine, showing our improved means for removing stock therefrom, the said means being shown partially in elevation and partially in section. And

Fig. 3 is an end elevation of the construction shown in Fig. 2.

In the several views similar reference characters refer to similar parts.

Beating engines are in use in which large rotary cylinders having holes formed in the periphery thereof are used for continuously removing the formed stock from the beating engine. When using beating engines of this type for forming stock for various grades of

paper from old papers and other similar material, difficulty has been experienced by reason of the fact that these old papers contain strings, rags, etc., which collect on the periphery of the cylinder which removes the formed stock from the beating engine and thus prevents the entry of the formed stock into the cylinder. Means have been provided for scraping or otherwise removing these strings and rags from the surface of

the cylinder referred to. This means for disposing of the strings and rags in the pulp is for several reasons unsatisfactory, and it is one of the objects of our invention to provide a cylinder for removing the stock from beating engines, of such construction that the strings and rags will not adhere thereto, nor will they pass into the cylinder.

Referring to Fig. 1, where we have conventionally illustrated an ordinary beating engine equipped with our invention, the reference character 5 indicates the tank of the beating engine, which is divided by a partition 6 in a manner well known. The reference character 7 indicates the shaft of the beater roll 8, which is journaled in the bearing blocks 9. This shaft is driven by any suitable means, as, for instance, the belt pulley 10. The construction thus far described is well known in this art, and forms no part of our invention, except as it enters into the combination recited in the appended claims.

Our novel means for removing the formed stock from the beating engine is in the form of a cylinder, indicated as a whole by the reference character 11. This cylinder comprises two end members 12 and 13 respectively, spaced apart upon the shaft 14, which is rotatably mounted in suitable bearings 15, one of which is secured to the partition 6, and the other of which is secured to the wall of the tank 5. The periphery of the cylinder is formed of a plurality of cylindrical rollers 16, which are rotatably mounted in the end members 12 and 13 by means of pins 17, which find bearings in the annular segmental bearing blocks 18 that are secured to the peripheries of the end members 12 by means of suitable screws 19 (see Fig. 3). The inner sides of the bearing blocks 18 are provided with flanges 20 which extend over the adjacent ends of the rollers to prevent the strings and rags from becoming wound about the pins 17.

The interior of the cylinder formed by the means just described is divided into a plurality of compartments by radially extending partitions 21, which are secured to the ends of the cylinders and extend radially from a point adjacent the rollers 16 to a point adjacent the shaft 14. The compartments formed by the partitions 21 are provided with plates 22 which form bottoms for these compartments when these compart-

ments are in position to discharge their contents through the openings 23 formed in the end member 12, adjacent the center thereof. It will be noted from an inspection of Figs. 5 2 and 3 that these plates are inclined from points adjacent the periphery of the end member 13 to points adjacent the center of the end member 12. Strips 21' are secured to the outer ends of the partitions 21, and 10 project in the direction of rotation of the cylinder. These strips 21' co-act with the partitions 21 to form scoops for retaining the stock which enters the cylinder between the rollers 16 and carry it to a point above 15 the center of the cylinder. The shaft 14 extends through a bell, into which the openings 23 discharge the stock. This bell discharges the stock and water contained therein into the trough 24 which leads to a stuff 20 chest or any other suitable means for receiving the stock.

Any suitable means may be used for rotating the cylinder 11, and in the accompanying drawings we have illustrated this cylinder as being rotated from the shaft 7 of the 25 beating engine. To do this we mount a counter shaft 25 in suitable bearings secured to one of the bearing blocks 9. This shaft is provided at one end with a pulley 26, which 30 is driven from the shaft 7 by means of a belt 27. The pinion 28 is secured to the other end of the shaft 25, and meshes with a suitable gear 29, which is secured to the shaft 14. By this means the cylinder 11 is 35 rotated in a direction opposite to the direction of rotation of the beater roll 8, or in other words, the portion of the cylinder 11 which dips beneath the surface of the stock in the tank 5 moves in the same direction as the 40 stock in this tank.

In operation, the formed stock passes between the rollers 16, which are spaced apart different distances, depending upon the character of the stock that is being formed, 45 and into the compartments formed by the radially extending partitions 21. As the wheel continues to rotate, this stock is carried upwardly by means of the scoops formed by the partitions 21, and the strips 21', until it reaches a position adjacent the top of the cylinder, whereupon it slides down the inclined plates 22 by gravity and is discharged through the corresponding opening 23 in the end member 12, into the bell, and from thence into the trough 24. It will thus be seen that we have provided 55 very simple means for delivering the stock from the beating engine to the trough 24.

We have found by experimentation that 60 very satisfactory results are obtained in the way of preventing strings and rags from adhering to the periphery of the cylinder, merely by the use of cylindrical members extending between the end members and not 65 rotatably mounted therein. Consequently,

we do not wish to limit our invention to the use of member 16 rotatably mounted in the end members 12, even though more satisfactory results are obtained by this construction. We do not know the exact reason why 70 the strings do not accumulate upon cylinders of this construction, but it is probably because less frictional contact is offered to the strings and rags than with cylinders having continuous peripheral portions. 75

While we have described the rotating member of our invention as being a cylinder, we wish it to be clearly understood that our invention is not confined to the use of a cylinder which is circular in cross section. 80 While the cylinders can perhaps be more economically constructed in this manner, our invention would function satisfactorily if it had an octagonal or other cross section. Furthermore, the roller 16 need not be circular in cross section but may similarly be made with any number of sides. 85

While we have described the details of the preferred embodiment of our invention, our invention is not to be limited to these details, 90 but is capable of other adaptations and modifications within the scope of the appended claims.

Having thus described our invention, what we claim is: 95

1. The combination with a beating engine of means for continuously removing the formed stock therefrom, comprising a cylinder mounted to rotate so that its periphery dips below the level of the stock in said engine, the said cylinder comprising a pair of end members, one of which is provided with a plurality of discharge openings adjacent the center thereof, a plurality of partitions dividing the space between said end 100 members into a plurality of compartments, strips secured to the outer ends of said partitions and forming scoops therewith, a plate in each compartment forming a bottom therefor when said compartment is in a position to discharge its contents, the said plates being inclined from points adjacent the periphery of one end member to points adjacent the center of the end member having the discharge openings, a plurality of 105 spaced cylindrical rollers forming the periphery of said cylinder, bearing members for said rollers secured to the peripheries of said end members, and means for rotating said cylinder. 110

2. The combination with a beating engine of means for removing the formed stock therefrom, comprising a cylinder mounted to rotate so that its periphery dips below the level of the stock in said engine, the said cylinder comprising a pair of end members, one of which is provided with a plurality of discharge openings adjacent the center thereof, a plurality of partitions dividing the space between said end members into a 115 120 125 130

- plurality of compartments, strips secured to the outer ends of said partitions and forming scoops therewith, a plate in each compartment forming a bottom therefor when 5 said compartment is in a position to discharge its contents, the said plates being inclined from points adjacent the periphery of one end member to points adjacent the center of the end member having the discharge openings, and a plurality of spaced 10 cylindrical rollers forming the periphery of said cylinder and secured to the peripheries of said end members.
3. The combination with a beating engine 15 of means for removing the formed stock therefrom comprising a cylinder mounted to rotate so that its periphery will dip below the surface of the stock in said engine, the said cylinder comprising a 20 pair of spaced end members, a plurality of spaced cylindrical rollers rotatably mounted in said end members to form the periphery of said cylinder, and means within said cylinder for lifting the stock to a position 25 from whence it is discharged by gravity through one of said end members of said cylinder, the said end member being provided with a suitable opening to permit of such discharge.
4. The combination with a beating engine 30 of means for removing the formed stock therefrom comprising a cylinder mounted to rotate so that its periphery will dip below the surface of the stock in said engine, the 35 said cylinder comprising a pair of spaced end members, a plurality of spaced rollers rotatably mounted in said end members to form the periphery of said cylinder, and means within said cylinder for lifting the stock to a position from whence it is discharged by gravity through one of said end members of said cylinder, the said end member being provided with a suitable opening to permit of such discharge.
5. The combination with a beating engine 40 of means for removing the formed stock therefrom comprising a cylinder mounted to rotate so that its periphery will dip below the surface of the stock in said engine, the 45 said cylinder comprising a pair of spaced end members, a plurality of spaced members rotatably mounted in said end members to form the periphery of said cylinder, and means within said cylinder for lifting the stock to a position from whence it is discharged by gravity through one of said end members of said cylinder, the said end member being provided with a suitable opening to permit of such discharge.
6. The combination with a beating engine 50 of means for removing the formed stock therefrom comprising a cylinder mounted to rotate so that its periphery will dip below the surface of the stock in said engine, the 55 said cylinder comprising a pair of spaced end members, a plurality of spaced members rotatably mounted in said end members to form the periphery of said cylinder, and means within said cylinder for lifting the stock to a position from whence it is discharged by gravity through one of said end members of said cylinder, the said end member being provided with a suitable opening to permit of such discharge.
7. The combination with a beating engine 60 of means for removing the formed stock therefrom comprising a cylinder mounted to rotate so that its periphery will dip below the surface of the stock in said engine, the said cylinder comprising a pair of spaced 65 end members, a plurality of spaced cylindrical members mounted in said end members to form the periphery of said cylinder, and means within said cylinder for lifting the stock to a position from whence it is discharged by gravity through one of said end members of said cylinder, the said end member being provided with a suitable opening to permit of such discharge. 70
8. The combination with a beating engine 75 of means for removing the formed stock therefrom comprising a cylinder mounted to rotate so that its periphery will dip below the surface of the stock in said engine, the said cylinder comprising a pair of spaced 80 end members, a plurality of spaced cylindrical members mounted in said end members to form the periphery of said cylinder, and means within said cylinder for discharging the stock through one of said 85 end members, the said end member being provided with a suitable opening for this purpose. 90
9. The combination with a beating engine 95 of means for removing the stock therefrom, comprising a cylinder mounted to rotate so that its periphery projects beneath the surface of the stock in said engine, the said cylinder comprising a pair of spaced members, a plurality of parallel spaced members secured to said first-named members, and forming slots extending parallel to the axis of said cylinder, and means within said cylinder for discharging stock from said cylinder to a point outside of said engine. 100
10. The combination with a beating engine 105 of means for removing the stock therefrom, comprising a cylinder mounted to rotate so that its periphery projects beneath the surface of the stock in said engine, the said cylinder comprising a plurality of parallel spaced members forming the periphery thereof, and extending parallel to the axis thereof, and means within said cylinder for discharging stock from said cylinder to a 110 point outside of said engine.
11. A cylinder for removing stock from a beating engine comprising a pair of end members, a plurality of spaced cylindrical members rotatably mounted in said end members to form the periphery of said cylinder, and means within said cylinder for discharging stock therefrom. 115
12. A cylinder for removing stock from a beating engine comprising a pair of end members, a plurality of spaced movable members mounted in said end members to form the periphery of said cylinder, and 120
13. A cylinder for removing stock from a beating engine comprising a pair of end members, a plurality of spaced cylindrical members rotatably mounted in said end members to form the periphery of said cylinder, and means within said cylinder for discharging stock therefrom. 125
14. A cylinder for removing stock from a beating engine comprising a pair of end members, a plurality of spaced movable members mounted in said end members to form the periphery of said cylinder, and 130

means within said cylinder for discharging stock therefrom.

13. A cylinder for removing stock from a beating engine comprising a pair of end members, a plurality of spaced members mounted in said end members and extending parallel to the axis of said cylinder to form the periphery of said cylinder, and means within said cylinder for discharging stock therefrom.

14. A cylinder for removing stock from a beating engine, comprising a pair of spaced end members and movable means mounted between said members in spaced relation to permit the entrance of stock within said cylinder and to hinder the entrance of strings and rags therewith.

15. Means for removing stock from a beating engine, comprising a cylinder having openings formed in the periphery thereof, a plurality of radially-extending ribs within said cylinder, forming a plurality of compartments, and a plate in each of said compartments extending from points adjacent the periphery of one end of such cylinder to points adjacent the center of the opposite end of said cylinder.

16. A cylinder for removing stock from

a beating engine, comprising a cylindrical member having spaced slots formed in the periphery thereof and extending substantially longitudinally thereof.

17. A cylinder for removing stock from a beating engine comprising a cylinder having slots formed in the periphery thereof and extending substantially longitudinally thereof, and means within said cylinder for raising the stock and delivering it through one end of said cylinder, the end of said cylinder being open for this purpose.

18. A cylinder for removing stock from a beating engine, comprising a plurality of elements extending substantially parallel with the axis of said cylinder, the said elements being spaced from each other and forming the periphery of said cylinder, and means within said cylinder for discharging the pulp therefrom.

In witness whereof, we hereunto subscribe our names this 18th day of January, 1919.

JAMES T. MURPHY.
EDWARD J. RANEY.
